HIS ATTORNEY

UNITED STATES PATENT OFFICE.

JOSE ANTONIO ALBISU, OF SALADILLO, ARGENTINA.

AIR-MOTOR.

1,302,889.

Specification of Letters Patent.

Patented May 6, 1919.

Application filed February 1, 1918. Serial No. 214,846.

To all whom it may concern:

Be it known that I, José ANTONIO ALBISU, a subject of the King of Spain, residing at No. 833 Belgrano street, Saladillo, Argentine Republic, have invented certain new and useful Improvements in Air-Motors, of which the following is a specification.

This invention relates to a novel air motor or aerial propeller and has for its object an improved device for utilizing the action of the wind as motive power.

The apparatus in accordance with this invention may be adapted for various uses, but for the clearer understanding of the following specification, the propeller has been shown in the accompanying drawings as operating in combination with an ordinary water pump.

In the said drawings,

20 Figure 1 is a side elevation of the propeller in accordance with this invention, applied to the top of the tower of a pump, and Fig. 2 is a plan view of the same.

In both of said figures, the same numbers 25 of reference have been used for indicating similar or corresponding parts.

1 is the framing of the tower which ends at its upper end with a plate or disk 5. 2 is the cylinder of the piston 11 of the pump 30 which has been suitably secured to the tower and carries at its upper end, on the plate or disk 5, a sleeve formed at its lower part with a flat surface 4, adapted to rotate on the upper disk 5 of the tower. Said sleeve

35 carries a bracket 3, forked at its upper end at 6, in which is mounted a horizontal axle 7 which rotatably supports the frame 8 of the propeller. The frame 8, substantially consisting of a bar or arm which extends in

40 the manner of a balance beam from both sides of the axle or pivot 7, has jointed to it at 9 the upper end 10 of the piston rod of the pump. At the opposite side, the propeller carries a reinforced frame 12 which

45 by means of two inclined stays 14 forms a triangular space 13, arranged on a vertical plane. The two stays 14 join at their outer ends and support a horizontal rod 15, perpendicular to the bar 8, to the ends of which

50 is connected a fork 17, adapted to turn on the studs 16 and carrying on its outer end an adjustable counterweight 20. Said fork 17 carries at its inner ends 18 a vane 19, adapted to move within the space 13 and the 55 upward and downward movements of which

are limited by the aforesaid stays 14. From the opposite end of the bar 8 is supported or is otherwise suitably secured thereto, a counterweight 21 which, together with a counterweight 22, arranged on the piston 60 rod of the pump, serves to maintain the device normally in horizontal equilibrium. The counterweight 20 has also been calculated to maintain the fork 17 and the vane 19 in horizontal equilibrium. Normally, 65 owing to the action of the said counterweights 20, 21 and 22, the apparatus assumes the position shown by full lines in Fig. 1. As soon as the wind blows, in any direction 70 whatever since the main support 3 is rotatable, the motor or propeller starts its operation.

Suppose the wind to flow in the direction of the arrow G, the vane D will be seized by the wind and tilted downward on the axle C, thereby causing the propeller to pivot on its axle B, in a corresponding direction, till it reaches its lowermost position, indicated by the broken lines E. The propeller or motor having arrived at this position the wind will act on the lower face of the vane 19 and by reaction at H, the propeller will rise, and reach its highest position indicated at F, after passing through the horizontal at D. On arriving at F, 75 reaction will take place in the reverse direction at 1, whereupon the motor will descend, thus producing a constant oscillatory motion, of a range sufficient to cause the piston 11 to pump the water. When the wind ceases, the whole of the device will return to the horizontal position shown by the full lines, owing to the action of the aforesaid 80 counterweights 20, 21 and 22.

It will be readily understood that the propeller or motor device in accordance with this invention may readily be adapted for many purposes other than that shown in the drawings, without departing from the limits of the invention. In the same manner, the 85 relative dimensions of the parts may also be modified and the equilibrium of the device may be produced in a different manner from that shown and described, independently of this invention.

The air motor or propeller in accordance with this invention may be used independently, as shown, or two or more of them may be connected in series, so as to obtain the combined operation of the same.

105

110

I now declare that what I claim as new and desire to secure by Letters Patent, is:

1. An air motor comprising a rocking beam, a vane mounted for rocking movement on the beam, means for limiting the movement of said vane, and means for biasing said vane and beam to a horizontal position.
2. An air motor comprising a rocking beam biased to a horizontal position, a frame formed on said beam and provided with an opening, and a vane mounted for rocking movement on said frame, said vane being

movable in said opening and biased to a horizontal position.

15

3. An air motor comprising a rocking beam biased to a horizontal position, a vertically disposed frame formed on one end of said beam, spaced stays carried by said frame, a vane mounted for rocking movement on said stays and disposed between the same, and means for biasing said vane to a horizontal position.

In testimony whereof I affix my signature.

JOSÉ ANTONIO ALBISÚ.
